UNITED STATES PATENT OFFICE

2,621,667

CONTAINER WASHING APPARATUS

Harry D. Lathrop, Chicago, Ill., assignor to The Lathrop-Paulson Company, Chicago, Ill., a corporation of Illinois

Application November 8, 1946, Serial No. 708,488

3 Claims. (Cl. 134—125)

1

This invention relates to container washing apparatus. The invention is particularly applicable to the washing of the exterior and bottoms of milk cans and other types of containers.

An object of the invention is to provide apparatus for effectively washing cans or other containers in a minimum of time and without requiring stoppage of the can as it is carried along a conveyor. Yet another object is to provide improved apparatus for washing the bottom and outer walls of a can or other container. Yet another object is to provide means automatically operated by a can for delivering wash fluid and for moving the stream of washing fluid with the can during its movement along a conveyor track. Other specific objects and advantages will appear as the specification proceeds.

The invention is illustrated, in a preferred embodiment, by the accompanying drawing, in which:

Figure 1 is a broken side view in elevation of a portion of a can washing machine equipped with conveyor apparatus; Fig. 2, a broken view showing the apparatus equipped with washing mechanism embodying my invention; Fig. 3, a top plan view of the apparatus shown in Fig. 2; Fig. 4, a perspective view of the valve control mechanism; and Fig. 5, a cross-sectional view of the conveyor track, taken on line 5—5 of Fig. 3.

In the illustration given in Figs. 1 to 5 inclusive, 10 designates a frame provided at its top with side rails 11 within which is a can-supporting track including parallel rails 12, as seen more clearly in Figs. 3 and 5. An endless conveyor 13, equipped with spaced dogs 13a, is carried by the conveyor chain 13b within channel member 13c for moving a can 14 upon the tracks.

The numeral 15 designates a can-inverting cradle shaft carrying the cradles 16 adapted to reverse the position of a can which has passed through the machine, with the neck downmost to the position illustrated in Fig. 1. Cradle shaft 15 is rotated through sprocket 57 by chain 58 which in turn is driven by suitable means (not shown). Since no claim is made to the can-inverting mechanism as part of the present invention, it is believed it will not be necessary to further discuss the details thereof.

The machine is equipped with pivotally-mounted arms 17 adapted to receive the bottom of the can 14 and to lower the same onto the track below. The arms 17 are provided with a counterweight 18 so as to halt the downward movement of the can 14 and ease the can gently onto the track.

2

As shown more clearly in Figs. 2 and 3, I provide mechanism for the washing of the can as it moves forward along the track and for moving the washing mechanism at the same time and in the same direction. In the illustration given, I provide a hollow pipe 19 providing a manifold therein which is mounted for rotation and which is equipped with an upwardly-extending drive arm 20. Connected to the drive arm is a connector rod 21 and a tube 22 receiving a spring 23. The spring is supported upon a rod 24 fixed to the slide bar 25. The slide bar 25 is guided between rollers 26 and is provided at its inner end with a cam roller 27. The roller engages a cam 28 mounted on the drive shaft 29. Upon rotation of the cam 28, the members 25, 24, 22 and 21 are reciprocated, thereby producing a rocking of the pipe 19.

The tube 19 is provided with a pair of upwardly-extending pipes 30, each having spray openings in the top portion thereof. The pipe 19 is also provided with two upwardly-extending pipes 31 equipped at their tops with a horizontally-extending tube 32 providing an elongated spray head. The tubes 32 are closed at their outer ends but provided with spaced openings 33 on their inner sides so as to direct a spray of liquid inwardly toward the cam.

The drive shaft 29 carries a second cam member 34 which drives a roller-equipped member 35 fixed to the end of rod 50 which extends through a spring 36 and slides within the other end of rod 50. The tube 37, as shown best in Fig. 4, is provided with a rotatably-mounted sleeve member 38 equipped with a laterally-extending arm 39 having a valve-engaging pin 40. The member 38 is provided with another arm 41 to which is pivotally connected a control rod 42. The weight of the arm 39 ordinarily causes the arm to remain at a low position and below the adjacent valve plunger 43 which controls the valve 44. The elements 35 through 42 and 49 are supported on frame 10 by rods 55 and 56 which are welded to tube 37, as shown more clearly in Fig. 2.

A tube 45 leads from the valve 44 to a pipe 46 entering the tube 19, as shown best in Fig. 3. A fluid supply line is indicated in Fig. 3 at 47 and leads from any suitable source of supply.

Power may be supplied to the drive shaft 29 by any suitable means (not shown), and transmitted through sprocket 48 fixed to shaft 29 to conveyor chain 13b.

The rod 42 extends upwardly to the level of the guide track so that when the can 14 is deposited by arms 17 one of the arms engages rod 42 and

depresses it to bring the wear pin 40 into alignment with the valve plunger 43. The relationship between the upper end of rod 42 and the arm 17 thereabove is indicated more clearly in Fig. 5. Preferably, a sleeve 49 is attached to the adjacent rail 12 to receive and guide rod 42, as indicated in Figs. 2 and 5.

Pins 51 and 52 are respectively fixed to rods 24 and 50 and slide within slots 53 and 54 in the tops of tubes 22 and 37. Normally, pins 51 and 53 remain in the position shown in Fig. 3 under the action of springs 23 and 36, but in case of jamming of the mechanism they permit rollers 27 and 35 to disengage from cams 28 and 34.

Operation

In the operation of the device, the can 14 on reaching the cradle is inverted, as illustrated in Fig. 1, so that the bottom of the can comes to rest upon the tracks 12 between the side rails 11. In the downward movement of the can 14, the weighted arms 17 ease the can gently upon the track and the conveyor dogs 13a engage the can and carry it forwardly, as illustrated in Fig. 1. As the can drops to the position here shown, the arm 17 above rod 42 engages the rod 42 and depresses it. This movement raises the arm 39 to bring the wear pin thereof into alignment with the plunger 43 of the valve 44. Meanwhile, shaft 29 is in continuous operation, and the cam 34 is reciprocating the member 37 forwardly and backwardly. When the arm 39 is raised, the pin 40 is brought into engagement with the plunger 43 and the valve is opened. Water or other washing fluid now passes from the supply line 47 through valve 44, hose 45, and into the manifold pipe 19. At the same time, the cam 28 is being rotated to reciprocate the members 22 and 21 and thereby rock the pipe 19.

The timing of the cams illustrated is such that the pipes 30 and 31 are in rear position when the can is deposited and move forwardly with the can as it is carried along the conveyor. This position is shown in dotted lines in Fig. 2 with pipes 31 inclined toward the left. It will be understood that members 30 and 31 may move pari passu with the can 14 or they may move slightly faster or at a slightly less speed. I prefer to have the members 31 and 30 start at about the rear of the can so as to throw a spray thereon and to slightly exceed the speed of the conveyor so that they spray the front of the can in the final washing action. The final position of pipes 32 is shown in dotted lines in Fig. 2 with pipes 31 inclined toward the right. If desired, the operation may be reversed with respect to the relative speed of the can and the washing spray members. However, I prefer to have the members move somewhat in unison with the can so that the washing action is continuing during the travel of the can. Thus, no time is lost in the washing step while at the same time a thorough washing of the outer surface and bottom of the can is accomplished by reason of the traveling washing devices. In the illustration given, can 14 remains in contact with arms 17, and thus continues to depress rod 42 until the swing of pipes 30 and spray heads 31 is completed from left to right as indicated in Fig. 2.

The washing step is particularly effective for the exterior of the can and after it has been through the washing machine where the interior thereof has been cleansed and sterilized, because with the operation described the water striking the exterior of the can does not splash into the

can but washes downwardly along the sides and over the bottom thereof.

While in the foregoing specification, I have described one embodiment of the machine in considerable detail for the purpose of illustrating the invention, it will be understood that such details may be varied widely by those skilled in the art without departing from the spirit of my invention.

10 I claim:

1. In an apparatus for washing the exterior surfaces of cylindrical containers such as milk cans, the combination comprising a conveyor for moving said containers along a generally horizontal path with the cylindrical surfaces of said containers substantially perpendicular to said path, a pipe providing a manifold rockably mounted below said path and extending transversely thereof, a spray pipe carried by said manifold on each side of said path and extending upwardly to the level of said containers, an elongated spray head carried by each of said spray pipes and extending at approximately right angles thereto adjacent said containers so that when said spray pipes are vertical said spray heads are horizontal, said spray heads having a plurality of longitudinally extending apertures therein oriented to direct streams of liquid on said containers, said spray pipes normally being inclined in a direction opposite to the direction of movement of said containers, and means for rocking said manifold pipe from said normal position in the direction of movement of said containers at an angular velocity great enough to cause said spray heads to traverse arcuate paths from the rear to the front of said containers as they are moved over said manifold-providing pipe by said conveyor, whereby substantially all of the cylindrical surfaces of said containers opposite said spray heads can be effectively washed by said spray heads.

2. The combination of claim 1 in which said rockably mounted, manifold-providing pipe is also equipped intermediate said spray pipes on each side of said path with at least one additional spray pipe extending upwardly from said rockably mounted pipe in alignment with said spray pipes on each side of said path but terminating below said path in a spray head provided with apertures adapted to direct the streams of water upwardly against the bottom of said containers.

3. In an apparatus for washing the exterior surfaces of cylindrical containers, the combination comprising a conveyor for moving said container along a generally horizontal path with the cylindrical surfaces of said containers substantially perpendicular to said path, a manifold pipe rockably mounted below said path and extending transversely thereof, a spray pipe carried by said manifold pipe on each side of said path and extending upwardly to the level of said containers, laterally extending spray heads carried by said spray pipes adjacent said containers so that the inclination of said spray heads with respect to said containers varies as said spray pipes and spray heads are moved through arcuate paths, said spray pipes normally being inclined in a direction opposite to the direction of movement of said containers, and means for rocking said manifold pipe from said normal position in the direction of movement of said containers at an angular velocity great enough to cause said laterally extending spray heads to traverse arcuate paths from the rear to the front of said containers as they are moved over said manifold pipe by said

conveyor, whereby substantially all of the cylindrical surfaces of said containers opposite said spray heads can be effectively washed by said spray heads.

HARRY D. LATHROP.
